DESIGN FOR A GAME BOARD

Emile Malisse, Detroit, Mich.

Application February 24, 1938, Serial No. 75,390

Term of patent 14 years

To all whom it may concern:

Be it known that I, Emile Malisse, a citizen of the United States, residing at Detroit, in the county of Wayne and State of Michigan, have invented a new, original, and ornamental Design for a Game Board, of which the following is a specification, reference being had to the accompanying drawing, forming part thereof.

Fig. 1 is a plan view of a game board showing my new design.

Fig. 2 is a sectional view taken on line 2—2 of Fig. 1.

Fig. 1 has been lined for color, the vertical, solid lines indicating red, the diagonal lines indicating green, the horizontal lines indicating blue and the interlaced lines indicating yellow.

I claim:

The ornamental design for a game board, as shown and described.

EMILE MALISSE.
